UNITED STATES PATENT OFFICE.

FREDERICK H. THURBER, OF NEWARK, NEW JERSEY, ASSIGNOR, BY MESNE ASSIGNMENTS, TO GURNEY ELECTRIC ELEVATOR COMPANY, OF HONESDALE, PENNSYLVANIA, A CORPORATION OF PENNSYLVANIA.

ELEVATOR-BRAKE.

1,066,744.

Specification of Letters Patent. Patented Mar. 3, 1914.

Application filed April 6, 1911. Serial No. 619,229.

To all whom it may concern:

Be it known that I, FREDERICK H. THURBER, a citizen of the United States, and a resident of Newark, in the county of Essex and State of New Jersey, United States of America, have invented certain new and useful Improvements in Elevator-Brakes, of which the following is a specification.

My invention relates to elevator brakes, and its object is to improve upon devices of this type and to provide a simple arrangement of parts for bringing a driven mechanism to rest quickly and smoothly without subjecting it to sudden strain.

I will describe my invention in the following specification and point out the novel features thereof in the appended claims.

Referring to the drawings, Figure 1 is a side elevation, partly in section, of a brake mechanism made according to my invention. In Figs. 2, 3 and 4 I have shown my improved brake in three of its operative positions to illustrate its operation.

Like characters of reference designate corresponding parts in all of the figures.

10 designates a base or other fixed portion of the machine to which my brake is applied.

11 is a brake-sheave affixed to a rotary shaft. In elevators, this brake sheave is usually a part of a coupling between the motor shaft and the shaft of the rest of the hoisting apparatus.

12, 12 are brake-shoes held in arms 13, 13, the lower ends of which are pivotally connected to the base 10. The upper ends of these pivoted arms are connected by links 14, the lengths of which are adjustable, with opposite ends of the lever 15. This lever is centrally pivoted at 16 to a stationary bracket which is affixed to some part of the elevator or other machine.

17 is an actuating lever rigidly affixed to or an integral part of the lever 15. This actuating lever may be moved up and down to release and apply the brake-shoes to the rotary sheave 11 by any suitable means. For example, an eye-bolt 18, and may be adjustably affixed to the plunger or core of a solenoid magnet 19, which, when energized, will raise the plunger and the lever 17 to release the brake, and when deenergized, will allow the plunger to drop to lower the lever and to apply the brake.

The parts thus far described are in com-

mon use and are well known. In order to 55 have the brake-shoes forced against the sheave 11 with sufficient pressure, it is customary to provide a weight or spring to pull down upon the lever 17. When this is done it has been found desirable to provide some 60 means of causing the action of such spring or weight to take effect gradually. Ordinarily, a dash-pot results in delaying the first application of the brake-shoe.

It is one of the objects of this invention 65 to retain the advantages of such constructions without their attendant disadvantages.

20 designates a vertically movable bar which passes through an opening near the end of the actuating lever 17. In the upper 70 end of this bar is a slot 21.

22 is a pin which passes through the lever 17 and freely through this slot. The bar, therefore, has a lost-motion connection with the actuating lever. On the bar are a plurality of weights 23, more or less of which may be used to suit the requirements of any particular case. The lower end of the bar 20 is connected to the piston 24 of an air dash-pot, and this is mounted upon the 80 base 10.

26 is a valve which opens during the upward movement of the piston so that its movement in this direction is not retarded, and 27 is an adjustable air outlet by means 85 of which the rate of the downward movement of the piston may be regulated.

28 is a cover for the weights and the upper part of the cylinder 25 of the dash-pot. A tension spring 30 is connected between the 90 actuating lever 17 and a lug 29 projecting from the side of the bar 20. This connection may be made by fastening one end of the spring to a plate 31 on the pin 22, and its other end to a threaded rod 32 which passes 95 through the lug and is provided with an adjusting nut 33, by means of which the tension on the spring may be varied.

I will now point out the operation of the device. When the actuating lever 17 is 100 raised to move the brake-shoes away from the brake sheaves 11, the pin 22, engaging the upper end of the slot 22, will raise the bar 20, the weights 23, and the piston 24, which are connected therewith. At the same 105 time the tension on the spring 30 will be increased. The parts are shown in these relative positions in Fig. 2. Now, when it

is desired to apply the brakes, the bolt 18 is allowed to drop. The spring 30, acting downwardly upon the pin 22, will immediately pull the actuating lever downward 5 and will cause the brake-shoes to be applied to the brake sheave. The weight of the bolt 18 and the parts which are connected with it assist in this part of the operation, and the slot 21 is of sufficient length to allow 10 the pin 22 to move freely downward. In fact this pin never strikes the lower end of the slot. In Fig. 3 the brake-shoes are shown applied and the parts in the relative positions just described. As soon as the actuating lever thus drops to apply the brake-shoes, the weights 23 and the rod 20 are free to move downward, but their movement will be retarded by the action of the dash-pot. As they move down, the top of the 15 slot engages with the pin 22, as is shown in Fig. 4, so that the weights will gradually force the actuating lever 17 farther down to apply a powerful braking effect to the brake sheave. It may be seen that by this arrangement the advantage of a slow-moving heavy weight upon the actuating lever is retained without the formerly attendant lapse of time in applying the brakes. The 20 brake-shoes are instantly applied and begin to exercise their retarding effect as soon as the operator starts the braking operation, so that the rotating member is slowed down, and this retarding effect is then followed up by the more powerful agency of the 25 weighted bar 20.

What I claim is.—

1. A brake, an actuating lever therefor, means for moving the lever to release the

brake, combined with a weight having a resilient connection and a lost-motion positive 45 connection with said lever, and a retarding device associated with said weight.

2. A brake, an actuating lever therefor, means for moving the lever to release the brake, combined with a bar connected to said 45 lever by a lost-motion connection, a weight connected to said bar, a spring connecting the actuating lever and the bar, and a dash-pot for retarding the movement of the weight in one direction. 50

3. A brake, an actuating lever therefor, means for moving the lever to release the brake, a pin projecting from said lever, a weight, a bar connected therewith, said bar being constructed with a slot through which 55 said pin projects, a dash-pot for retarding the movement of the weight in one direction, and a spring connecting the actuating lever and the bar.

4. A brake, an actuating lever therefor, 60 means for moving the lever to release the brake, a pin projecting from said lever, a weight, a bar connected therewith, said bar being constructed with a slot through which said pin projects, a dash-pot for retarding 65 the movement of the weight in one direction, means for regulating the action of said dash-pot, and an adjustable tension spring between the pin and said bar.

In testimony whereof I have signed my 70 name to this specification in the presence of two subscribing witnesses.

FREDERICK H. THURBER
